UNITED STATES PATENT OFFICE.

MYRTLE SELDERS, OF HABANA, CUBA.

STOPPER DEVICE FOR WASHBOWLS.

No. 866,230.

Specification of Letters Patent.

Patented Sept. 17, 1907.

Application filed January 28, 1907. Serial No. 354,564.

To all whom it may concern:

Be it known that I, MYRTLE SELDERS, a citizen of the United States, residing at Habana, Republic of Cuba, have invented new and useful Improvements in

5 Stopper Devices for Washbowls, of which the following is a specification.

This invention relates to stopper devices for stationary wash bowls, and the primary object of the invention is to provide simple and effective means for replacing the usual plug and the inconveniences attending the latter by locating a movable stopper in the outflow pipe a short distance below the outlet opening of the wash bowl.

By the use of the improved stopper the water can be released from the bowl without requiring the hands to be placed in the water to remove the stopper and furthermore the bowl can be used with freedom without liability of displacing the stopper as is frequently done when the ordinary loose stopper or plug is employed.

20 The improved stopper is always in place and is readily operative to close or open the outflow pipe, and furthermore, it is situated at such an elevation above the trap that injurious gases will be prevented from returning into the bowl and also dirty water that may remain in the trap is prevented from flowing back into the bowl.

With these and other objects in view the invention consists in the construction and arrangement of the several parts which will be more fully hereinafter set forth.

In the drawing, Figure 1 is a side elevation of a bowl 30 broken away in parts and showing the features of the invention. Fig. 2 is a horizontal section taken in the plane of the line 2—2, Fig. 1.

Similar characters refer to like parts throughout the views.

35 The numeral 1 designates an ordinary wash bowl as commonly employed and found in lavatories, bath rooms and the like and having a central outlet 2 at the bottom which in the present instance is covered with a screen 3.

40 Connected to the bottom of the bowl over the outlet opening is an outlet pipe 4 continuing into or forming a part of a trap 5 connected to a suitable pipe 6.

At a short distance below the outlet 2 of the bowl a disk valve 7 is mounted and formed with diametrically opposed trunnions 8 having movable bearing in opposite portions of the pipe 4, the one trunnion 8 having a handle or turning head 9 connected thereto and located at the front portion of the bowl within easy reaching distance of the user of the bowl.

Surrounding the periphery of the disk 7 is a hard 50 rubber ring 10 which forms a tight joint with the inner surface of the pipe 4 to prevent leakage of the water therethrough.

The closure just described and comprising the disk 7 and ring 10 is reversible in its movement and is prevented from being completely overthrown in opposite directions by reversely arranged stops 11 at a suitable distance below the closure and projecting inwardly from the pipe 4. When the bowl is used for washing purposes the closure is in the position indicated by Fig. 60 2 or horizontally across the pipe. When it is desired to liberate the contents of the bowl the closure is turned so that the disk will assume a vertical position and in view of the fact that the said closure may be moved in either one of two directions a great advantage will result and the disk and its ring are relieved of any strain that might be imposed on the closure if it only had movement in one direction. The dirty water passing out from the bowl runs through the screen 3 and pieces of soap or any other sediment is prevented from entering the outlet pipe and clogging the latter. As before stated the disk and its ring when in closed position prevent the escape of gases through the bowl. Furthermore, boiling water can be sent out of the bowl with a single turn of the closure embodying the features of the 75 invention without burning the hands and which could not be done if the hands had to be immersed in the water to remove the ordinary plug.

The improved device is comparatively simple and is materially economical in its service as it is not liable 80 to become lost or stolen, and furthermore, bowls and outlet pipes now in use may be equipped with the improved attachment at a minimum cost.

What I claim is:

The combination with the waste pipe of a wash bowl, of 85 a flat disk-like closure therefor disposed in a horizontal plane and having on opposite sides pintles that project through the pipe to permit swivel movements of the closure, one of the pintles being provided with a finger hold, a non-oxidizable annulus combined with the disk 90 and of a size to impinge closely against the inner walls of the pipe, and stops diagonally arranged on the pipe with which the closure engages to limit its movements.

In testimony whereof, I affix my signature in presence of two witnesses.

MYRTLE SELDERS.
